UNITED STATES PATENT OFFICE.

MILLARD F. STOWE, OF COLDWATER, MICHIGAN, ASSIGNOR TO COLDWATER SPECIALTY MANUFACTURING COMPANY, OF COLDWATER, MICHIGAN.

SHINGLE CARRIER AND SUPPORT.

No. 926,364.

Specification of Letters Patent.

Patented June 29, 1909.

Application filed September 12, 1906. Serial No. 334,288.

To all whom it may concern:

Be it known that I, MILLARD F. STOWE, a citizen of the United States, residing at Coldwater, county of Branch, and State of Michigan, have invented certain new and useful Improvements in Shingle Carriers and Supports, of which the following is a specification.

This invention relates to improvements in shingle carriers and supports.

10 The main object of this invention is to provide an improved shingle carrier which is adapted to be used to carry shingles and also to hold or retain them on a roof.

15 Further objects, and objects relating to structural details, will definitely appear from the detailed description to follow.

I accomplish the objects of my invention by the devices and means described in the following specification. The invention is 20 clearly defined and pointed out in the claims.

A structure embodying the features of my invention is clearly illustrated in the accompanying drawing, forming a part of this specification, in which,

25 Figure 1 is a side elevation of my improved shingle carrier. Fig. 2 is an inverted plan. Fig. 3 is an enlarged perspective of one of the brad plates 4. Fig. 4 is an enlarged detail taken on a line corresponding to line 4—4 of 30 Fig. 3, showing means for securing the brad plates to the band. Fig. 5 is a perspective of my improved shingle carrier or sling filled with shingles.

In the drawing, similar reference characters refer to similar parts throughout the several views.

Referring to the drawing, 1 represents the body or band portion of my improved shingle carrier or sling preferably formed of canvas.

40 At each end of the band are handles 2 which are adapted to be brought together, as is illustrated in Fig. 5, for carrying shingles.

45 At one end of the band, the lower end when the sling is in position to serve as a holder on a roof, are longitudinally arranged upwardly curved bars 3. These bars prevent the slipping of the shingles from the band, when the same is laid out upon the roof in use. On the under side of the band and preferably 50 adjacent to these bars 3 are brad plates 4 having brads 5 and 6 punched up thereon.

The brads 6 are arranged through the band and are clenched down to retain the plates. They are preferably also further secured by 55 suitable rivets arranged through a central

opening 7 therein. This forms a very light and at the same time strong sling or carrier, and one which effectively supports the shingles on the roof, and at the same time can be readily moved about on the roof or 60 carried from place to place as may be desired. Another advantage is that it can be folded very compactly for storage or transportation.

I have illustrated and described my improved sling in detail in the form preferred by me on account of its structural simplicity and economy and convenience in use. I am, however, aware that it is capable of considerable variation in structural detail without departing from my claims.

Having thus described my invention, what I claim as new and desire to secure by Letters Patent is:

1. The combination of a flexible band 75 having handles at each end thereof; a pair of curved bars secured at one end of said band, said bars being arranged longitudinally with their outer ends projecting upward; and a plurality of plates having brads punched up on both sides thereof secured to the under side of said band adjacent to said bars by rivets arranged centrally therethrough and by inserting the brads on their inner sides through the band and clenching 85 the same thereon, as specified.

2. The combination of a flexible band having handles at each end thereof; a pair of curved bars secured at one end of said band, said bars being arranged longitudinally with 90 their outer ends projecting upward; and a plurality of plates having brads punched up on both sides thereof secured to the under side of said band adjacent to said bars by inserting the brads on their inner sides 95 through the band and clenching the same thereon, as specified.

3. The combination of a flexible band having handles at each end thereof; a pair of curved bars secured at one end of said band, 100 said bars being arranged longitudinally with their outer ends projecting upward; and a plurality of plates having brads punched up on both sides thereof secured to the under side of said band adjacent to said bars, as 105 specified.

4. The combination of a flexible band having handles at each end thereof; a pair of curved bars secured at one end of said band, 110 said bars being arranged longitudinally with

- their outer ends projecting upward; and a plurality of brads secured to the under side of said band adjacent to said bars, as specified.
5. The combination of a flexible band having handles at each end thereof; and a plurality of plates having brads punched up on both sides thereof secured to the under side of said band by rivets arranged centrally therethrough and by inserting the brads on their inner sides through the band and clenching the same thereon, as specified.
6. The combination of a flexible band having handles at each end thereof; and a plurality of plates having brads punched up on both sides thereof secured to the under side of said band by inserting the brads on their inner sides through the band and clenching the same thereon, as specified.
- 10
- 15
7. The combination of a flexible band 20 having handles at each end thereof; and a plurality of plates having brads punched up on both sides thereof secured to the under side of said band, as specified.
8. The combination of a flexible band 25 having handles at each end thereof; means for holding one end of said band in an elevated position when it is extended; a plurality of brads secured to the under side of said band.
- 30
- In witness whereof, I have hereunto set my hand and seal in the presence of two witnesses.

MILLARD F. STOWE. [L.S.]
